(57) CLAIM

The ornamental design for a stemware holder, as shown and described.

DESCRIPTION

FIG. 1 is a front view of the decorative curved stemware holder showing the new design, when the curved stemware holder is empty;

FIG. 2 is a bottom view thereof, when the curved stemware holder is empty;

FIG. 3 is a left-side view thereof, when the curved stemware holder is empty;

FIG. 4 is a perspective view thereof, when the curved stemware holder is empty;

FIG. 5 is a front view of the decorative curved stemware holder showing the new design, when the curved stemware holder is holding a wine glass;

FIG. 6 is a bottom view thereof, when the curved stemware holder is holding a wine glass;

FIG. 7 is left-side view thereof, when the curved stemware holder is holding a wine glass; and,

FIG. 8 is a perspective view thereof, when the curved stemware holder is holding a wine glass.

The broken lines are for illustrative purposes only and form no part of the claimed design.
